UNITED STATES PATENT OFFICE

JAMES F. GLASS, OF CONROE, TEXAS

WORK TABLE AND CLAMP

Application filed March 13, 1930. Serial No. 435,555.

This invention relates to a table and clamp which is mainly designed to hold grain doors while they are being constructed, the general object of the invention being to provide a flange at the rear side of the table and a movable flange at the front thereof, with a lever arranged at the rear of the table and so connected with the movable flange that when the lever is moved in one direction, the said movable flange will be caused to clamp the object on the table between itself and the rear flange.

This invention also consists in certain other features of construction and in the combination and arrangement of the several parts, to be hereinafter fully described, illustrated in the accompanying drawings and specifically pointed out in the appended claims.

In describing the invention in detail, reference will be had to the accompanying drawings wherein like characters denote like or corresponding parts throughout the several views, and in which:

Figure 1 is a top plan view of the table.

Figure 2 is a rear view thereof.

Figure 3 is a section on line 3—3 of Figure 1.

Figure 4 is a section on line 4—4 of Figure 1.

Figure 5 is a bottom plan view showing the crank means operated by the turning of the lever.

In these views, the letter A indicates the table and 1 indicates a flange connected with the rear part of the top of the table and 2 indicates a flange connected with one end of the table. A movable flange 3 is arranged at the front of the table and is fastened to the bars 4 which pass through the transverse grooves 5 formed in the table top and which are covered by the plate 6 which covers the table top. The rear ends of these bars are turned upwardly, as shown at 7, and they are fastened to the ends of a curved bar 8. Bolts 9 pass through holes in the turned up ends 7 and are threaded into holes in the flange 1. Springs 10 are carried by these bolts and engage the turned up ends 7 so that these springs normally hold the bars 4 and the movable flange 3 in their rearward limit of move-

ment. A support 11 is connected to the rear flange 1 and an upright 12 is rotatably arranged in the support and has a handle 13 connected with its upper end. A disk 14 is connected with the lower end of the upright and carries a crank pin 15 which passes through a hole in a bar 16, the other end of the bar being fastened to the central part of the bar 8.

Thus it will be seen that by turning the upright or shaft 12 by the lever or handle 13, the crank pin will exert a pull upon the bar 16 so that the bar 8 is moved toward the table and this movement is communicated to the flange 3 by the bars 4 so that said flange is moved outwardly to permit an object to be placed on the table and then by releasing the handle or lever 13, the springs 10 will move the bars 4 rearwardly and thus cause the flange 3 to clamp the object on the table between itself and the stationary flange 1. Attention is called to the fact that the clamping flange 3 is at the front of the table and that the operating parts are at the rear thereof, so that these parts will not be in the way of the workmen at the front of the table. The springs will cause the clamping flange 3 to firmly grip the object so that there is no danger of the parts working loose, as the door is being nailed together so that the door is tight when finished.

It is thought from the foregoing description that the advantages and novel features of the invention will be readily apparent.

It is to be understood that changes may be made in the construction and in the combination and arrangement of the several parts, provided that such changes fall within the scope of the appended claims.

What I claim is:

1. A device of the class described comprising a table having a stationary flange at its rear side, a movable flange at the front side, bars passing through the table and connected with the movable flange, springs associated with the rear parts of the bars for holding the flange in clamping position and means at the rear of the table for moving the bars forwardly against the action of the springs to move the front flange forwardly.

2. A device of the class described comprising a table having a stationary flange at its rear side, a movable flange at the front side, bars passing through the table and connected with the movable flange, springs associated with the bars for holding the flange in clamping position, means at the rear of the table for moving the bars forwardly against the action of the springs to move the front flange forwardly, such means comprising a bar connecting the rear ends of the first mentioned bars together, a shaft having a crank pin thereon, a bar pivoted to the pin and to the connecting bar and a handle on the shaft for turning the same.
3. A device of the class described comprising a table, a stationary flange at the rear edge of the top of the table, a movable flange at the front of the table top, bars passing through the table and connected with the front flange, the rear ends of the bars extending beyond the table and having their ends bent upwardly, bolts carried by the table and passing through the bent-up ends of the bars, springs on the bolts and bearing against the turned up ends for holding the bars in their rearward position, an upright shaft journaled in the rear part of the table, a handle on the upper end of the shaft, a crank pin at the lower end of the shaft, a cross bar connecting the rear ends of the first mentioned bars together and a bar pivoted to the crank pin and connected to the central part of the cross bar.

35 In testimony whereof I affix my signature.
JAMES F. GLASS.
